(57) **CLAIM**

The ornamental design for a chemical warfare agent detector, as shown and described.

DESCRIPTION

FIG. 1 is a front, right, and top perspective view of the chemical warfare agent detector embodying the new design; FIG. 2 is a rear, left, and bottom perspective view thereof; FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is a front, right, and top perspective view of the chemical warfare agent detector shown in an alternate configuration with a sample cartridge attached;

FIG. 10 is a rear, left, and bottom perspective view thereof; and,

FIG. 11 is a right side view thereof.

The broken lines in the figures are shown for the purpose of illustrating portions of the chemical warfare agent detector, optional accessories, a sample cartridge, and/or environmental matter and form no part of the claimed design.
